UNITED STATES PATENT OFFICE.

ABRAHAM W. LOZIER, OF NEW YORK, N. Y.

STYLOGRAPHIC PEN.

SPECIFICATION forming part of Letters Patent No. 283,155, dated October 12, 1880.

Application filed July 3, 1880. (No model.)

To all whom it may concern:

Be it known that I, ABRAHAM W. LOZIER, of New York, in the county and State of New York, have invented a new and useful Improvement in Fountain-Pens, of which the following is a specification.

Figure 1 is an enlarged side view, partly in section, of my improved fountain-pen. Fig. 2 is a longitudinal central section of the pen. Fig. 3 is a detached side view of the lower part of the pen. Fig. 4 is an enlarged central section of the lower part of the pen.

My invention is intended to and does obviate many objectionable features now found in the ordinary fountain or stylographic pens, some of which defects are the following: The pens are costly, as the point is tipped with platinum or iridium, which is liable to break off in use and tedious to repair. The spring forcing the writing-point to position is apt to weaken through oxidizing. The ink is not strained before coming into the minute passage near the point and soon clogs the same. The pens break joint near the writing-end and soil the fingers with the ink when opened to be filled and while filling. The top cap must be removed each time to obtain an air pressure, and in order to fill the pen a separate glass filler must be used and carried about in a separate receptacle.

The construction of my improved pen is as follows, reference being had to the drawings: A is the hollow tube, handle, or shell of the pen, provided with screw-threads or joints a and a' at each end, and near the upper end with an outside surrounding band, B, of polygonal contour. This band is preferably of rubber, and constitutes a cushion. It also prevents the pen from rolling when laid down.

40 Into the tube A, through the upper open end, is inserted the filler C, which is composed of a tube, b, of smaller diameter than A, and tapering nearly to a point, c, at the lower end, with a small opening there. This tube b, which is preferably of glass, is fastened by a flexible rubber collar, d, at its upper end, to a hollow head, g. This head g has upon it, just above the collar d, a screw or joint, which fits the screw or joint a at the upper end of the tube 45 A, and on the top of this head g is a smaller detachable hollow cap, e, which is inserted

into an upwardly-projecting nipple, f, of the head g. The hollow cap e, to prevent leakage through it, is of such shape that any ink which reaches it from within the filler C, if the pen 55 is in inverted position, will gather around an inwardly-projecting tube, h, before it can escape through the central air-hole, i.

When the filler C, constructed as above stated, is taken out of the tube A, it constitutes a convenient filler for supplying the tube A with ink. When in position, as in Fig. 2, the filler, having a continuous air-passage from the top opening, i, to the lower opening, c, admits air to the pen sufficient to allow a free 65 flow of ink from the lower writing-point of the pen. The cap e prevents ink from flowing into the pocket of the wearer, as stated.

I prefer to provide a groove, j, at the side of the tube f, to permit the ready application of D to f while writing without cutting off air-supply.

Within the tube b, I prefer to place two filters, k and l, which are porous, expansive plugs, placed at a distance from each other, 75 and which serve a double purpose. When the filler is placed over a reservoir of ink to be filled, the ink passes through the lower porous plug, l, and is thereby strained. When the filler is in the tube A, and the pen used, a 80 partial vacuum is created between the two plugs k and l, thereby slightly retarding the flow of the ink.

m is a rubber band or other cushion placed around the tube b to prevent it from striking 85 the tube A and lessen the danger of breaking the tube b, which, as stated, is preferably of glass.

The lower filtering-plug, l, is preferably composed of wicking or cord, one end of which 90 is carried down through the aperture c, and then up to and beneath the cushion m. This cord can be drawn out more or less as occasion requires. By jointing the tube b to its head g by the rubber pipe d and providing its 95 lower part with the cushion m all danger of breaking it is avoided.

If the tube b is made of glass, a graduated scale is preferably marked on it to show the amount of ink within and the amount of writing for which it suffices.

Into the screw a', at the lower end of the tube

A, is screwed the hollow piece or writing-nipple E. (Shown of large size in Fig. 3.) Through this extends the wire or writing-spindle *n*, which serves for the pen-point at *n*^x, where it emerges from the lower end of E, and which extends upward above the piece E, so as to be readily pulled out and reinserted when E is unscrewed. This writing-spindle *n* has coiled around its upper part a spring, *o*, resting at the lower end upon a sliding tube, *p*, but free at the upper end. The tube *p* is of less diameter than the interior of tube E. Into the sliding tube *p* is screwed a screw, *q*, through which passes, and into which is soldered, the wire *n*. When the wire *n* becomes shortened by the wearing of its writing-end, by simply screwing the screw *q* down out of the tube *p* the writing-point is kept at proper length for writing, or it may be entirely screwed up into the seat beyond the inner opening of the pen, so as to use the pen as a simple gravity-pen without a spindle-point.

The spring *o* holds the tube *p* upon an inner seat in tube E, unless pressure from below raises said tube off the seat. Into the upper end of the piece E is screwed another tube, *s*, which embraces and protects the upper end of the wire *n*, and bears against the upper end of the spring *o*, and thus serves to increase or lessen the force of the spring, as may be necessary. The screw-tube *s* contains within it a filter, *t*, and is made sectional so as to allow the ready removal, cleaning, and replacement of the filter. When the piece E and tube *s* are fastened together in position a continuous passage runs through them, making, in connection with the parts already described, a continuous hollow passage from end to end of the pen as soon as tube *p* is raised off its seat.

The cap D, which fits over the lower end of the piece E, protects the wire point *n*^x, and has at its bottom a bed of soft material, *u*, against which the point *n*^x can rest.

In the use of my pen I first obtain a supply of ink by unscrewing and taking out the complete filler C. The point *c* of this is dipped in the ink-bottle and ink is gathered within it by suction or gravity. A supply of ink having thus been obtained, the filler C is reinserted and screwed into its place in the tube A. Upon the cap D being removed the pressure of the atmosphere through the opening in the cap-piece *e*, and the hollow tube *l* permits the ink to flow freely downward through the entire apparatus and through the filter *t* therein contained, and around the tube *p*, when the same is raised, down to the point *n*^x, which acts as a pen-point and applies the liquid upon the substance written on.

From the foregoing description the advantages of my improvements are evident. There need be no unscrewing of the top piece to obtain air-pressure, for that comes through the cap-piece *c*. The filler C for the pen is carried with it or within it, not separately, and

this filler is saved from danger of breaking by the band *m* and the flexible collar *d*. The ink is thoroughly filtered at *k*, *l*, and *t* before it reaches the narrow passage near the point. The surrounding band B, by its shape, prevents the pen from rolling.

The distance to which the point *n*^x shall project is perfectly and easily regulated by the screw *q* and spring *o*, and the long upward extension of the wire *n* renders it easily removable from its receptacle. The point at which the pen is filled is remote from where it is grasped, thus avoiding soiling by the ink. Finally, the wire *n* may be removed, and the pen used for marking, having as its point the opening through which the wire projected, or the filler C may be used alone as a marking pen.

The cap *c* may, in many cases, be dispensed with.

The tube *s* may be perforated at the sides above the filter *t*.

The ink is free to flow as soon as the style *n* is pressed upon paper and the tube *p* raised off its seat. In the space around the tube *p* the ink is free to flow down.

I claim—

1. A fountain-pen combined with the filler C, which is inserted within it and at all times open at both ends, substantially as herein shown and described.

2. The filler C, composed of a tube, *b*, neck *d*, head *g*, and hollow cap *e*, substantially as herein shown and described.

3. The filling-tube *b*, having flexible neck *d*, and head *g*, in combination with the pen-case A, as set forth.

4. The combination of the filler-tube *b*, and its flexible neck *d*, and its head *g*, with the embracing-cushion *m*, and outer tube A, substantially as herein shown and described.

5. In a fountain-pen, the combination of the shell A with the filler C, and with the filter *t* contained therein, said filter being removable from the shell A, together with the filler, substantially as herein shown and described.

6. The tube E, having inner sliding tube, *p*, of reduced diameter, in combination with the writing-spindle *n*, screw *q*, spring *o*, and adjusting-screw *s*, substantially as herein shown and described.

7. The sectional screw-tube *s*, constructed substantially as described, in combination with the filter *t*, writing-spindle *n*, spring *o*, screw *q*, seat *p*, and tube E, substantially as herein shown and described.

8. The ink-holding tube *b*, combined with a cord, which is passed through its lower discharge-orifice, and held taut by an outer ring, *m*, substantially as set forth.

ABRAHAM W. LOZIER.
